GRILL

Oscar Philipe, Northwood, England, assignor to Anglo-Swiss (Equipment Production) Limited, London, England

Filed June 9, 1972, Ser. No. 261,563

Claims priority, application Great Britain Apr. 28, 1972

Term of patent 14 years

Int. Cl. D7—02

U.S. Cl. D55—1 E

FIG. 1.

FIG. 2.

FIG. 1 is a perspective view of the grill taken from the front and above showing the top and front thereof; and

FIG. 2 is a perspective view of the grill taken from one side and above showing the top and one side thereof.

The bottom and rear of the grill are plain and the other side of the grill corresponds to the side shown in the drawings.

I claim:

The ornamental design for a grill, substantially as shown and described.
